CLAIM

The ornamental design for a skylight inner frame, as shown and described.

DESCRIPTION

FIG. 1 is a perspective view of the skylight inner frame; FIG. 2 is an end elevation view of the skylight inner frame; and,

FIG. 3 is an opposite end elevation view of the skylight inner frame shown in FIGS. 1 and 2, with the skylight inner frame installed in conjunction with glazing panels, seals, and an outer frame depicted, all of which are shown in broken lines. The broken lines represent environmental structure that forms no part of the claimed design.

The appearance of any portion of the skylight inner frame beyond the break line shown in FIG. 1 forms no part of the claimed design.
